INVENTOR:

Jacob Pfitzinger

United States Patent Office

JACOB PFITZINGER, OF BUFFALO, NEW YORK.

Letters Patent No. 70,015, dated October 22, 1867.

COAL-HOD.

The Schedule referred to in these Letters Patent and making part of the same.

TO ALL WHOM IT MAY CONCERN:

Be it known that I, JACOB PFITZINGER, of the city of Buffalo, county of Erie, and State of New York, have invented a new and improved Coal-Hod; and I do hereby declare that the following is a full and exact description thereof, reference being had to the accompanying drawings, making a part of this specification, in which—

Figure I is a bottom plan view.

Figure II is a vertical section.

Figure III is an end elevation.

The nature of this invention consists, first, in making a malleable iron bottom, having an aperture and hinged valve, with projecting handle for operating the valve, and a short pipe connection for conducting the coal from the hod into the stove; second, attaching a skeleton frame to the lower part of the hod, upon which the hod is supported, and by means of which the hod may be set upon the stove, and the valve left free to work and discharge the coal into the stove.

Having reference to the drawings, the letter A represents the main body of the hod, which may be made in any common and well-known form and manner. B represents an aperture made through the bottom, which may be of any required diameter. This bottom is made of malleable iron. C represents a door or valve, which is hinged to the bottom, as shown at c¹. It has a projecting handle, by which it is moved to open or close it, as shown at c². This valve may be round to correspond with the opening, and a little larger in diameter, and it may be made a little dishing to catch the dust and drippings from the coal, if there should chance to be any. D represents a short pipe projecting from the opening to guide the coal into the stove or furnace. E is a skeleton frame which is attached to the bottom of the hod, and upon which the hod stands sufficiently elevated to allow of the free working of the valve, and give room for the projection of the discharge pipe. The handle of the valve projects through the frame. This frame may be made of cast metal malleableized, or it may be made of small bars or rods of wrought iron, as may be preferred. The bail of the hod is shown at F.

A coal-hod constructed as herein described is less liable to scatter coal upon the floor, and requires less labor and fatigue in supplying a stove or furnace with coal, and is more economical and cleanly in use than those heretofore constructed.

What I claim as my invention, and desire to secure by Letters Patent, is—

A coal-hod having a malleable iron bottom, B, valve C, short pipe connection D, and skeleton frame E, substantially as herein described.

JACOB PFITZINGER.
